UNITED STATES PATENT OFFICE.

JULIUS GOODMAN, OF BALTIMORE, MARYLAND.

REVERSIBLE CUFF.

1,279,330.

Specification of Letters Patent. Patented Sept. 17, 1918.

Application filed March 28, 1916. Serial No. 87,157.

To all whom it may concern:

Be it known that I, JULIUS GOODMAN, a citizen of the United States, residing at Baltimore, in the State of Maryland, have 5 invented certain new and useful Improvements in Reversible Cuffs, of which the following is a specification.

This invention relates to an improvement in combined shirt-cuffs and shirt-sleeves.

10 The object of this invention is to provide a novel construction of cuff that shall be detachable from the wrist-band of a shirt-sleeve, that shall be foldable longitudinally so that the flap-part of the cuff 15 may be made to assume a reverse position from one side to the other.

When the flap-surface that is outward has become soiled, the entire cuff may be removed from the wrist-band and reversed 20 with respect to the wrist-band and then re-attached thereto and the flap-part folded over to place the soiled surface of the flap inward and the clean surface thereof outward.

25 This improvement in cuffs has particular reference to what are termed "soft shirts," or unstarched, with soft cuffs.

The invention is illustrated in the accompanying drawing, in which,—

30 Figure 1, is a view of the cuff spread open flat, and a portion of one surface broken away to show lining.

Fig. 2, is a view of the shirt-sleeve and its wrist-band.

35 Fig. 3, is a view of one half of a cuff showing the bifurcated or double attaching edge spread open.

Fig. 4, is a side view of one half of the cuff attached to the wrist-band.

40 Fig. 5, shows a portion of the two flaps of the bifurcated edge of the cuff spread wide open flat, to indicate the different positions of the two rows of sockets.

45 Fig. 6, is a section showing the flap part of the cuff folded and attached to the wrist-band as when worn.

Fig. 7, is a view of the stud and socket.

The shirt sleeve is designated by the 50 numeral 7, and the wrist-band 8, is permanently attached to the end of the sleeve. The wrist-band and sleeve-end have a placket-slit 9, as usual, and when the placket slit is closed it is fastened by means of a button 10, and button-hole 11.

55 The cuff 12, is shown in Fig. 1, spread out flat; one longitudinal half of the cuff

has a lining 13, shown in Fig. 1, where the outer ply 14, is broken away; the other half has no lining.

The three plies in the longitudinal half 60 where the lining is may be called the folding flap 15, because this part of the cuff folds over as in Fig. 6.

The edge 16, of the lining 13, extends longitudinally along the center of the cuff 65 and serves as a guide-edge on which the flap-part 15, folds. The lining is held in its place by stitches 17, near the longitudinal and end edges; also the guide-edge 16, of said lining is secured to one of the outer 70 plies 14, by a line of stitches 18, which prevent said lining from shifting its position, and forming wrinkles that would show exteriorly in an unsightly manner.

The longitudinal edge 19, of the cuff 75 which fastens to the wrist-band 8, is bifurcated, that is instead of being one edge it is a double edge as shown in Figs. 3, 4 and 5, such double edge being obtained by splitting the thicknesses of the cuff longitudinally, thus producing two edges which taken together have an inverted V-shaped formation; a line of stitches 20, extends longitudinally of the cuff along the top or joining part of said two bifurcated edges. 80 When the cuff is fastened to the wrist-band the inverted V-edge straddles the edge of the wrist-band 8, and conceals the latter from view, and also entirely conceals the metal fasteners. 90

The wrist-band 8, of the sleeve is provided on its interior face with a row of stud-members 21, of a two-member metal fastener. In the present instance five stud-members are permanently secured to the wrist-band. These stud-members engage their counterpart socket-members 22, which are secured to the bifurcated edges, or double edges 19, of the cuff, and within said inverted V-shaped split formation. The stud-members 21, have their bases attached onto the interior face of the wrist-band, as shown, the stud itself projecting from the center of the base will enter the hole of a socket-member 22, on the cuff. 100

105 The cuff is provided with two rows of socket-members 22, one of said rows being secured within the inverted V-shaped split to the inner face of one part of the bifurcated edge and the other row of socket-members being likewise secured to the other part of said double-edge. 110

These two horizontal rows of socket-members 22, are shown in Figs. 1 and 5; when looking at the outer surface of the cuff as an article, the socket-members cannot be seen, but in the drawing, Fig. 1, they are indicated in dotted circles and the socket-members on one double-edge appear above the row of socket-members on the other double-edge.

10 This different position of the two rows of socket-members 22, on the two parts of the bifurcation, affords the advantage that when the socket-members of the lower row are engaged with the studs on the wrist-band 8, the cuff itself will be lower or farther down on the wrist of the person wearing it; and again when the socket-members of the upper row are engaged with the studs, the cuff itself will be shorter, or 15 higher on the person's wrist. This different adjustment enables the wearer of the cuff to secure a more satisfactory fit.

In Fig. 5, the two parts of the bifurcated edge 19, are shown spread away oppositely 20 from their top where they are joined together, and both parts in this Fig. 5, lie flat in the same plane.

It will be understood that when these two parts of the bifurcation have the inverted 25 V-shaped position, the upper and lower horizontal edges of Fig. 5, will then be together, as in Figs. 1 and 4, then the sockets 22, on one part will not overlap or touch the sockets on the other part.

At each end the cuff has two button holes 35 23, 24, and these two holes are equi-distant from the folding guide-edge 16, of the lining, which when the cuff is folded brings the two holes at the same end into coincidence, and when the opposite ends of the 40 cuff are brought together a cuff-button may be inserted through all four of the button-holes.

Having described my invention what I 45 claim is,

The combination with a shirt sleeve having a wrist-band, of a series of snap-fastener stud-members secured around the inner side of the wrist-band; a cuff provided along one edge with two separable flaps, a series of 50 socket members secured to the inner face of one of said flaps; another series of socket members secured to the inner face of the other of said flaps said two series of socket members being concealed between said flaps 55 and the socket members on one flap being located nearer the free edge of the flap to which they are attached than are the socket members on the other flap so that the two sets of socket members are located in different horizontal planes with respect to the detachable edge of the cuff.

In testimony whereof I affix my signature in the presence of two witnesses.

JULIUS GOODMAN.
